CLAIM

The ornamental design for a urinary catheter, as shown and described.

DESCRIPTION

FIG. 1 is a perspective view of a urinary catheter, showing the new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a bottom plan view thereof; and,

FIG. 7 is a top plan view of the thereof.

In the drawings, the dashed broken lines represent portions of the urinary catheter that form no part of the claimed design.
